SLIDE AWAY TABLE AND HOLDING FRAME
THEREFOR

John G. Prince, Schofield, Wis.

Application September 2, 1949, Serial No. 113,691

3 Claims. (Cl. 311—19)

1

This invention relates to collapsible furniture, and more particularly pertains to a wall mounted table construction, the table top being hinged for movement along the wall and retraction against the wall.

The primary object of the present invention is to provide a collapsible table that may be pulled from a retracted position where it is supported on a wall to the operative position.

Another important object of the present invention is to provide, in accordance with the foregoing object, a table which may be selectively positioned along the wall, while remaining in the operative position and attached to the wall.

Another important object is to provide a table in conformity with the foregoing objects having hinging means and supporting means, whereby the table may be moved with a minimum of effort.

An important feature of the present invention is the use of a single rod for slidably guiding, supporting, and pivoting the table top.

These, together with various ancillary features and objects of the invention which will later become apparent as the following description proceeds, are attained by the present invention, a preferred embodiment of which has been illustrated by way of example only in the accompanying drawings, wherein:

Figure 1 is a perspective view of the invention showing the same attached to a wall and in the retracted or closed position;

Figure 2 is another perspective view of the invention showing the same attached to a wall with the table in the operative position, with parts being shown in dotted outline;

Figure 3 is another perspective view similar to Figure 2, but showing the table shifted to the left;

Figure 4 is a vertical transverse sectional view taken substantially upon the plane of the section line 4—4 of Figure 1;

Figure 5 is a fragmentary horizontal sectional view taken substantially upon the plane of the section line 5—5 of Figure 3; and,

Figure 6 is a fragmentary detail sectional view of the leg roller arrangement and is taken substantially upon the plane of the section line 6—6 of Figure 4.

Reference is now made more specifically to the accompanying drawings, wherein like numerals designate similar parts throughout the various views, and in which the numerals 10 and 12 designate a wall and floor respectively.

A frame 14 having an opening 16 is suitably secured to the wall as by countersunk screws 18.

10 The opening 16 is adapted to receive a table top 20. Although numerous materials can be used in making the frame 10 and table top 20, the preferred construction uses ply wood in the interests of light weight, strength and resistance to warping. Economy in labor and materials is attained by being able to form the frame 14 and table top 10 from a single piece of material, as will be seen in Figure 1. The frame 14 is also provided with a slot 22 for a purpose to be later set forth, which will incidental to its other uses provide easy means for saw access to fabricate the frame and table top from a single piece of material.

15 As shown in Figures 1, 2, and 4, a leg 24 is hinged to the underside of the table top 20 by hinges 26, being cut out as at 28 to form end portions 30. As best shown in Figure 6, the ends of the portions 30 are grooved as at 32 to receive rollers 34 which are pivoted by pins 36 which extend through the end portions 30.

20 A rod 38 has one end supported on and is spaced from the wall 10 by a suitable support such as bracket 40. The rod 38 extends along the wall through the slot 22 and opening 16 into a recess 42 in the frame 14 and is attached therein by a suitable fastener extending through a bore 44 that is provided through the rod 38 and frame 14, such as the screw 46 which also serves to hold the frame 14 on the wall 10.

25 The inner or lower end of the table top 20 is concaved as at 48 to slidably embrace the rod 38 (see Figure 4), and is provided with countersunk hinge straps 50 for slidably embracing the rod 38 and retaining the same in the concaved portion 48.

30 From the foregoing it will be understood that the table top 20 is free to pivot in a vertical plane about the rod 38 when in the position shown in Figures 1 and 2 and in addition is free to be moved longitudinally along the rod 38, when in the operative position of Figures 2 and 3, as it will be seen at once that the slot 22 is of sufficient width to accommodate the thickness of the table top 20. The sliding movement along the rod 38 is facilitated by the outer end of the table being supported on rollers 34, which are parallel to the rod 38. It is to be noted that as the table top 20 is moved from the Figure 1 position to the Figure 2 position that the leg 24 will swing by gravitation about its hinges 26 to the supporting position and vice versa.

35 Additional sliding support and anti-friction action is given the table top by the provision of a bearing strip 52 suitably secured along the edge of the slot 22 and the opening 16, and a bearing strip 54 secured along the underside of the table

top 20 as shown in Figure 4. The end of strip 52 is upturned and apertured as at 56 to receive and give additional support for the rod 38. In addition the upturned end serves as a stop or spacing means for limiting inward sliding movement of the table top 20.

A bumper 58 may be placed in the opening 16 and attached to the frame 14 as shown in Figures 2 and 3 for cushioning the closing of the table top or limiting the movement of the same in the opening 16 in the event the table top 20 is of less thickness than the frame 14. In addition a conventional latch is employed to retain the table top 20 in the closed position. The preferred arrangement having a latch bolt 60 operative to extend into the opening 16 by handle 62, and a recess 64 in the edge of the table top 20 to receive the latch bolt 60.

In addition to preferably forming the frame 14, the table top 20, and the leg 24 of ply wood, which will of course, be suitably painted or otherwise finished to present an attractive appearance, it is contemplated to have all metallic parts, such as the rod 38, the bearing strips 52 and 54, and the bracket 40 chromium plated to further enhance the beauty of this article of furniture.

It will be understood that the device may be constructed so that the table may be moved to the right instead of to the left as shown in the drawings. It is of course contemplated that slot 22 may be formed in each side of the frame 14, with the rod 38 being supported at each end by bracket 40.

Although the table top has been depicted as being substantially rectangular, it will be appreciated that the principle of this invention lends itself to numerous peripheral configurations of the table top such as being triangular, ironing board-shaped or the like. Furthermore it is not desired to imply that the table will find utility only as an eating table or the like, even though such will probably be the normal use, but will undoubtedly be of great value wherever a working surface is desired that may be shifted about and readily removed to conserve space.

It is also to be noted that the frame 14 may be positioned about an inset shelving space (not shown) in registry with the opening 16, so that the table top 20 will function as a door thereof.

The present invention lends itself particularly well to be incorporated with prefabricated walls or panels for buildings, trailers, or the like. It being understood in this connection that the frame may in itself be a portion of the wall if desired or separately attached thereto, the wall being appropriately grooved and cut out to receive the table top and rod in the former case.

From the foregoing, the construction and operation of the device will be readily understood and further explanation is believed to be un-

necessary. However, since numerous modifications and changes will readily occur to those skilled in the art after a consideration of the foregoing description and drawings, it is not desired to limit the invention to the exact construction shown and described, but all suitable modifications and equivalents may be resorted to, falling within the scope of the appended claims.

Having described the invention, what is claimed as new is:

1. A folding table construction adapted for mounting on a wall, comprising a vertical frame mountable on a supporting wall and having an opening therein, said frame having a horizontal slot in one side, a pivot rod extending through said slot and across the opening and having a first end secured to the side of said frame opposite the slot, a support bracket carried by the second end of said rod for securing the rod in spaced relation to said wall, a table top of substantially the same size as said opening and having one end hingedly connected to said rod and being slidably supported thereon for movement longitudinally of the rod and also being pivotally receivable in said opening, and means for supporting the other end of said table top.

2. The combination of claim 1 including a bearing strip secured to the frame adjacent the lower edge of said opening having an upturned end for limiting the sliding movement of the table top on the rod, said upturned end having an aperture for receiving said rod therethrough, a second bearing strip secured to the underside of the table top for sliding engagement with first said bearing strip.

3. The combination of claim 1 including latch means in said frame adjacent said opening for releasably retaining said table top in said opening, and a bumper in said opening for limiting the pivotal movement of the table top therein.

JOHN G. PRINCE.
